UNITED STATES PATENT OFFICE.

CHARLES C. HANSON AND JOHN TWARDOWSKY, OF CHICAGO, ILLINOIS, ASSIGNEES,
BY MESNE ASSIGNMENTS, TO UNIVERSE CORPORATION, OF CHICAGO, ILLINOIS, A
CORPORATION OF ILLINOIS.

COMPRESSOR.

Application filed May 13, 1921. Serial No. 469,110.

To all whom it may concern:

Be it known that we, CHARLES C. HANSON, a citizen of the United States, and JOHN TWARDOWSKY, a citizen of Russia, both residing at Chicago, in the county of Cook and State of Illinois, have invented certain new and useful Improvements in a Compressor; and we do hereby declare the following to be a full, clear, and exact description of the invention, such as will enable others skilled in the art to which it appertains to make and use the same.

Our invention relates to compressors of the general class employed for compressing gases or gaseous mixtures and in its general objects aims to provide a simple, durable and easily manufactured compressor affording numerous advantages over the compressors now in common use.

20 In one important aspect, our invention aims to provide simple and effective means for retarding a leakage of the compressed gas alongside the piston used for compressing the same, and aims to provide this without employing packing rings or auxiliary parts of any kind.

In another aspect, our invention aims to provide an exceedingly simple, cheap and easily manufactured valve for controlling the discharge of the compressed gas and aims to mount this valve so that it will automatically be operated by pressure differences. In this aspect, our invention aims to employ the head of the compressor cylinder as the valve, aims to provide an exceedingly simple and substantially frictionless mounting for such a valve member, and aims to utilize particles of the gas for cushioning this valve member so as to eliminate both jarring and noises. Furthermore, our invention aims to provide a valve member (desirably as a combined cylinder head and movable valve member) which will not require highly exact machining and which will afford the required spaces for such cushioning particles of the gas.

50 In still another aspect, our invention aims to provide an unusually compact mounting for the cooling chamber employed for cooling the compressed gas, and for this purpose aims to provide a mounting secured directly to the cylinder of the compressor and serving also as a guide and stop for the valve of the compressor.

Still further and also more detailed objects will appear from the following specification and from the accompanying drawing, in which—

Fig. 1 is a vertical section through a compressor embodying our invention, taken along the axis of the compressor cylinder and at right angles to the shaft of the compressor.

Fig. 2 is a section taken at right angles to Fig. 1 but on a reduced scale.

Fig. 3 is a fragmentary section similar to that of Fig. 1 and showing another method of carrying out that part of our invention which relates to the reducing of leakage past the piston of the compressor.

Fig. 4 is a section similar to Fig. 3 but taken with the piston near the point at which it affords the maximum compression.

In the embodiment of Figs. 1 and 2, the compressor of our invention includes a compression cylinder 1 which is desirably cast integral with the crank chamber 2 and which is equipped at its upper end with a flange 3 arranged for bolting a cap casting 4 to the top of the cylinder. Bolted to the crank housing 2 is a head 5 carrying a tubular bearing 6 which extends beyond the inner and outer faces of the head 5 and in which the crank shaft 7 is journaled. To secure an adequate bearing for this crank shaft, I desirably make the bore of the bearing tube 6 considerably larger in diameter than the shaft 7 and employ this tube as the bearing for a casting 8 which has the crank pin 9 integral with the same and which has a portion 10 of the casting extending through a transverse bore in the shaft 7. In making the parts for this purpose, the shaft 7 first has this transverse bore drilled through it near one end of the shaft and is then set into the mold employed for making the casting 8, so that the connecting portion 10 will be cast through the said bore as an integral part of the crank pin casting and hence will securely anchor this casting to the shaft.

At the other end of the bearing tube 6, the shaft 7 is here shown as journaled in a bushing 11 threaded into the said tube as shown in Fig. 2. This bushing 11 desirably has a counterbored end directed towards the inner end of the shaft and opposed to the correspondingly shaped end of

a sleeve 12 which is slidably interposed between the shaft and the bearing tube 6, so that this sleeve may be moved towards the bushing 11 for the purpose of compressing a suitable packing 13 interposed between the parts 11 and 12. This packing is desirably in the form of gaskets as indicated in the drawing, and the compressing movement is desirably imparted to the sleeve 12 by a spring 14 bearing at its other end against a ring 15 which is secured to the bearing tube 6 by screws 16. The shaft 7 also desirably has a pair of grooves disposed between the members 12 and 13 and spaced by a collar 17 so as to cooperate with the spring-pressed movement of the sleeve 12 in reducing leakage along the shaft, after the manner disclosed more fully in our copending application 20 #477,252 as filed June 13, 1921 on a stuffing box.

The cylinder 1 is desirably ground to an accurate cylindrical bore nicely fitting the simple cylindrical surface of the piston 18, this piston being here shown as hollow and as connected by a pin 19 to the connecting rod 20 which is pivoted at its other end on the crank pin 9. The cylinder 1 has at one side an inlet 21 threaded for direct connection to the inlet pipe 22 through which the compressible gas or other fluid is supplied, the connection between the cylinder and this inlet being so positioned that it will be substantially uncovered when the piston is at its lowermost point of travel as shown in Fig. 1 but will be entirely closed as soon as the piston has moved for some distance towards the head 23 of the cylinder.

With the parts thus arranged and with any suitable check valve arrangement at the head of the cylinder, it will be obvious that a movement of the piston from the position of Fig. 1 to that of Fig. 2 will afford a considerable compression of the gas in the cylinder. The resulting pressure will therefore tend to force a portion of this gas alongside the piston 18 into the crank casing 2, and in practice we have found that with the leakage of gas from the crank chamber 2 retarded by such a stuffing box arrangement as that of Fig. 2, the resulting pressure within the crank casing would soon reach a considerable amount. Consequently there will be an undesirable tendency towards a leakage of gas from the crank chamber. To avoid this, we desirably provide simple means for causing the major portion of the gas which leaks by the side of the piston to return to the inlet of the cylinder. For this purpose, we preferably provide the bore of the cylinder 1 with an enlargement in the form of a groove 23 having a relatively small portion thereof opening into the inlet 21 and having its major portion continuously closed by the exterior of the piston 18.

Thus arranged, it will be obvious from Fig. 2 that whatever gas leaks along the surface of the piston from the closed end of the latter will find a vent through the groove 23 into the inlet 21. Consequently, at the time of greatest compression, the leakage past the cylinder will spend itself mainly in returning some of the compressed gas to the inlet, while the pressure difference between the inlet and the interior of the crank casing will be too small to force any appreciable amount of gas through into the crank casing. Hence, instead of having the pressure within the crank casing reach or even exceed half of the maximum compression within the cylinder, the simple groove arrangement as above described enables us to reduce the pressure within the crank casing to only a few per cent of the said maximum compression. This in turn reduces the power required for returning the piston on its down stroke and also cooperates with the above described stuffing box arrangement in reducing the leakage along the shank 7 to a substantially negligible quantity.

Instead of employing a rigid cylinder head and a spring-pressed check valve of the usual type which requires a highly accurate grinding of the cooperating parts and close attention to keep it in proper working order, we desirably make the head of the compressor cylinder movable and make this head 24 function as the movable valve member also. For this purpose, we bolt a flange 4 of a cap member to the flange 3 at the upper end of the compression cylinder by screws 26, desirably interposing a layer of a suitable packing (such as tin foil) for preventing leakage between these flanges. This flange 4 forms the outer rim of a cap 28 overhanging the end of the cylinder and having integral with this cap a downwardly directed boss 29 extending to within a very small distance of the movable cylinder-head 24 so as to serve as a stop for limiting the upward movement of this cylinder head. The boss or stop portion 29 has a central and vertical bore 30 affording an outlet for the compressed gas delivered into the interior of the cap 28, and has threaded into it an elbow 105 31 which affords a connection from this outlet bore 30 of the bushing to a coil of piping 32 leading to an outlet nipple 33 shown in Fig. 2.

Instead of employing metal for the cylinder head 24, we desirably make the latter of a relatively softer material, such as vulcanized fiber, and desirably make this head of an outside diameter sufficiently smaller than the bore of the flange 4 so that it will be freely guided by this bore without requiring an accurate machining or involving an appreciable amount of noise or friction. Furthermore, we desirably taper the head 24 towards its upper edge as shown in the 120 125 130

drawings, so as to shorten the path of the compressed gas towards the bore 30 of the boss on the cap member.

By using a fiber head 24 of a thickness 5 approaching the vertical distance between the extreme upper end of the cylinder and the bottom of the boss 29 we can limit the movement of the said head to a quite small distance, thereby reducing the momentum 10 of the same and limiting the flow of gas under and over this head to passages which are almost capillary. Consequently, the compressed fluid discharged into the interior of the cap 28 when the head 24 is raised 15 will not be able to flow into the outlet bore 30 as rapidly as it reaches the interior of the cap past the extreme periphery of the fiber head, and will present a cushion of compressed air between the boss 29 and the head 20 24 which will cooperate with the residual pressure within the cap 28 in preventing a lifting of the head 24 prior to the time at which the piston closely approaches the upper end of its stroke. We therefore secure 25 a relatively high compression with an exceedingly simple construction and with an arrangement entirely free from springs or other auxiliary moving parts.

Moreover, we have found in practice that 30 the top of the fiber head need not be machined to a surface accurately conforming to the bottom of the boss 29, as slight irregularities are advantageous in affording air spaces which will serve as cushions for 35 the fiber head when lifted. So also, in case dirt or chips should get into the cylinder, these are apt to be pounded into the body of the fiber by the up and down movement of the fiber head, so that such solid impurities will not interfere materially with a proper working of the movable head in its function of a valve.

Besides affording a receiving chamber for 40 the compressed gas and a stop for limiting the movement of the cylinder head, the cap member of our compressor also desirably supports a casing 33 which freely houses a coil 32 of piping. This piping can be cooled continually by water admitted through an 45 inlet 34 and passing around the piping and the cap 28 to an outlet 35, thereby cooling the gas which had become heated while being compressed and also cooling the cap into 50 which the compressed fluid is first discharged from the compressor cylinder. For these cooling purposes, we desirably provide the casing 33 with an annular flange 36 adapted to be secured to the flange 4 of the cap member by screws 37 extending through 55 a metal ring 38, the joint between the flanges 4 and 36 being sealed by a rubber packing ring 39. By thus utilizing the cylinder of the compressor as a direct support for the cooling chamber, we are enabled to 60 produce an easily constructed, simple and

compact arrangement particularly desirable in certain types of compressors such as those designed for use in connection with household refrigerators.

From the above it will readily be seen 70 that the novel features of our simple construction accomplish highly desirable results:

1. By employing the cylinder head itself as the check valve of the compressor, we 75 reduce the number of required parts, entirely eliminate the need of any spring in connection with the valve and permit an exceedingly cheap construction.

2. By discharging the compressed fluid 80 first into the chamber over the cylinder head, we allow this charge of fluid to flow gradually into the piping of the system while the piston is making the major portion 85 of a complete reciprocation, thereby steadyng the flow of compressed fluid.

3. By using a movable valve member of 90 large diameter and correspondingly large stops for limiting the movement of this member, we reduce the wear due to the pounding and also reduce the movement required for this valve member.

4. By employing vulcanized fibre or the like for this combined cylinder head and movable valve member, we greatly reduce 95 both the noise and the possibility of trouble due to dirt, soot, or the like.

5. By grooving either the cylinder or the piston we avoid any considerable loss of the 100 fluid past the piston.

6. By using the cap 28 also as part of the cooling chamber we secure an exceedingly inexpensive and compact cooling arrangement and one in which the cooling water simultaneously cools the fluid in the piping 105 32, the cap 28 and the fluid within the said cap.

However, while we have heretofore described our invention in a desirable embodiment combining various novel features, we 110 do not wish to be limited to the combination of all of these novel features, nor to the details of construction and arrangement as above disclosed, since various modifications might obviously be made without departing 115 from the spirit of our invention. For example, Figs. 3 and 4 show a cylinder and piston arrangement in which the leakage-retarding groove is transferred from the cylinder to the piston, being in the form of a groove 40 formed in the periphery of the piston at a height which will cause this groove to open into the inlet 21 when the piston is at or near its uppermost position. This groove arrangement will also provide 120 a vent for the compressed gas leaking alongside the piston from the closed end of the latter, but probably will be inferior to the arrangement of Figs. 1 and 2 since the groove will afford the connection to the in- 125 130

let only when the piston is near the top of its travel. Moreover, the arrangement of Figs. 3 and 4 will be more likely to carry oil into the inlet, it being desirable to fill the crank casing 2 to a considerable extent with oil. So also, we do not wish to be limited to the use of our compressor in connection with a refrigerating apparatus.

We claim as our invention:

- 10 1. In a compressor, a cylinder, a cap closing one end thereof, and a cylinder head positioned within the cap with freedom for slight movement in all directions, the cap having a head-movement-stopping portion in axial alinement with the cylinder and an outlet bore extending through the said stopping portion.
- 15 2. In a compressor, a cylinder, a cap closing one end thereof, and a cylinder head positioned within the cap with freedom for slight movement axially of the cylinder, the cap having integral therewith a bore portion laterally guiding the cylinder head and a boss axial of the cylinder for limiting the movement of the head away from the cylinder, the said boss having an axial bore affording the outlet for the compressed fluid from the cap.
- 20 3. In a compressor, a cylinder, a cap closing one end thereof, and a cylinder head positioned within the cap with freedom for slight movement axially of the cylinder, the cap having a bore portion laterally guiding the cylinder head and a boss axial of the cylinder for limiting the movement of the head away from the cylinder, the part of the cap connecting the said boss and bore portion being formed for affording a compressed gas receiving chamber of relatively

large size in proportion to the outlet of the 40 chamber.

4. In a compressor, a cylinder, a cap closing one end thereof, a cylinder head positioned within the cap with freedom for slight movement in all directions, the cap 45 having a head-movement-stopping portion in axial alinement with the cylinder, a cover carried by the cap and cooperating with the latter to afford a cooling chamber, and an outlet pipe disposed in the cooling chamber 50 and connected to the interior of the cap through a bore in the latter substantially axial of the cylinder.

5. In a compressor, a cylinder, a cap closing one end thereof, a cylinder head positioned within the cap with freedom for slight movement in all directions, means within the cap for limiting the movement of the cylinder head away from the cylinder, and a cooling chamber carried by the cap 55 and connected thereto through the said means.

6. In a compressor, a cylinder, a cap closing one end thereof, a cylinder head positioned within the cap with freedom for 60 slight movement in all directions, an outer casing carried by the cap and freely housing the cylinder-head-inclosing portion of the cap to afford a cooling chamber therebetween, piping disposed in the said chamber 65 and connected to the interior of the cap, and means for circulating a cooling liquid through the said chamber.

Signed at Chicago, Illinois, May 10th, 1921.

CHARLES C. HANSON.
JOHN TWARDOWSKY.
